AEROSOL APPARATUS FOR DECORATIVE COATING AND PROCESS FOR MAKING SAID APPARATUS

Albert L. Edelstein, New York, N. Y.

Application December 29, 1953, Serial No. 400,950

13 Claims. (Cl. 299—95)

The present invention relates (1) to an aerosol container unit for dispensing a surface coating spray for decorative purposes, and more particularly to a unit of this type for applying a coating to the surface of a Christmas tree or to other surfaces to simulate a snow covering or a plastic flocking by means of a stencil for giving various designs, and (2) to a method of producing such a unit.

Heretofore, in loading aerosol spray containers of the type described, the mixture of solids in loose subdivided or granular form is charged into the container in the required proportions, and the propellant in the form of a compressed liquified gas, or in the form of a liquid at sub-zero temperature, is introduced or poured into the container. The sudden evaporation of the liquid propellant as it comes into contact with the container creates pressure surges causing the loose subdivided solids to blow out of the container and into the atmosphere.

One object or feature of the present invention is to provide an aerosol unit for dispensing a surface coating spray containing solids in suspension or solution, the unit being constructed to facilitate loading of the container and capping the same without blowing out the solids therefrom into the atmosphere and to assure the charging of the container with the right amount of the solids and the proper proportions of the ingredients thereof.

Another object of the invention is to provide a method of producing an aerosol container unit of the general type described, which prevents the blowing of solids from the container into the atmosphere during loading and which assures the charging of said container with the right amount of solids and the right proportion of ingredients thereof.

In carrying out certain objects and features of the present invention, the solids are charged into the aerosol container in the condition of a preformed self-contained cartridge holding the ingredients in the right amounts and proportions and designed to disintegrate by the solvent action of the propellant and/or liquids miscible therewith, to allow their ready dispersion or solution therein. Hereinafter, by "propellant" is intended not only the main gas propellant having a low boiling point, such as Freon-12 (dichlorodifluoromethane) but also other liquids miscible and blended therewith to reduce the propelling vapor pressure of the liquid in the container and perhaps to increase the salient action of the liquid.

The cartridge is preferably in the form of a capsule or case for receiving solids in subdivided or granular form to be enclosed in the capsule. It is desired that at least a part of the capsule, case or cartridge is made of a material easily soluble in the propellant employed in the container. The cap of the capsule or case has at one or both ends, for example, a material soluble in the propellant, or the whole capsule or case may be of such soluble material. Under the action of the propellant, the case or capsule, or the soluble parts thereof dissolves, thereby permitting the propellant to reach the solids carried by the

case and dissolve or disperse them, so that they can be discharged from the container as part of a spray.

Various other objects, features and advantages of the invention are apparent from the following particular description and from inspection of the accompanying drawing, in which:

Fig. 1 is a section of an aerosol container spray unit embodying the present invention; and

Fig. 2 is a section of a cartridge adapted to be charged into the container of an aerosol unit and embodying the present invention.

Referring to the drawings, there is shown a container 10, which, per se, forms no part of the present invention and which may be of any well-known construction. In the form illustrated, the container 10 comprises a body 11 in the form of a cylindrical can having an opening 12 at the top, to which is crimped or otherwise attached, a valve cup 13 containing a valve 14 adapted to be opened by a valve stem 15 in the form of a resiliently-pressed thumb piece having a discharge opening 16.

Depending from the inlet of the valve 14 is a flexible standpipe 17 forming a unit with the valve cup 13 and extending in flexed condition to one side of the rounded bottom of the container body 11. Upon application of tilting pressure on the thumb piece 15 towards the outlet valve opening 16, the contents of the container are discharged from said opening in the form of a spray.

The drawing shows for the purpose of illustration one form of valve head 13 for the container 10, but it must be understood that this valve head may be of any other type, manipulatable in any other manner.

The container 10 holds a propellant 20 suitable for aerosol devices. Common forms of propellents, known as Freons, consist essentially of fluorinated hydrocarbon derivatives of the short chain and small ring aliphatic series of organic compounds and especially of the methane and ethane series. In the specific form illustrated, this propellant 20 consists essentially of dichlorodifluoromethane CCl_2F_2 (Freon 12). Since the vapor pressure of Freon 12 is high (70 lbs. per square inch gauge at 70° F.), requiring the use of containers of comparable strength, this Freon 12 is usually blended with other propellents having lower vapor pressure and miscible with the main propellant to permit the use of lighter containers. This blending propellant may, for example, be trichloromonofluoromethane CCl_3F (Freon 11) or methylene chloride having lower vapor pressure and serving also as a solvent for the solids in the cartridge.

Also the propellant may, as far as certain aspects of the invention are concerned, be of any suitable type, it must conform with certain requirements for the purpose of the present invention. It must be a solvent for those parts of the cartridge holding the solids together in the form of a self-contained unit against disintegration. If, for example, the cartridge has a case, at least part of which is designed to dissolve away under the solvent action of the propellant, then this propellant must obviously be a solvent for this part of the case, and must also serve as a solvent or at least must be able to disperse the solids into finely divided sprayable form.

As a feature of the present invention, the active solid ingredients of the aerosol container unit are embodied in the form of a self-contained unit or case or cartridge 22 designed to be charged as such into the container. In the specific form shown, this unit 22 is in the form of a capsule having an outer case or envelope 23 containing the solids 24 in finely divided form, as for example, in granular form. The case 23 which is small enough to fit into the container body 11 through its top opening 12 is shown in the form of a slender cylindrical tube 25 having a closure or cap 26 in the form of a disc closing its open end. The capsule tube 25 and cap 26 are made

of material easily soluble in the propellant used. A suitable material for this case tube 25 and cap 26 is polystyrene which is easily soluble in the propellant Freon 12 and Freon 11, and in methylene chloride when blended with Freon 12. The cap 26 may be sealed onto the tube 25 in any suitable manner, as, for example, with toluol, which is compatible with polystyrene for adhesive or sealing purposes.

Instead of making the entire case or cartridge 23 of material soluble in the propellant 20, only parts of the case may be made of soluble material. For example, the case tube 25 may be of insoluble material, such as polyethylene, cellophane, or cellulose acetate, while the cap or closure 26 may be of soluble material, such as polystyrene. If desired, the tube 25 may be made of insoluble material and may be open at both ends and closed at these ends with caps or discs of soluble polystyrene. In many instances, the tube 25 may be made of glass, or tin, or paper, or fiber, or tin foil, or aluminum, or aluminum foil, or of any other suitable material for the purpose. If desired, the tube 25 may be made with perforations which are filled with materials that are soluble in the propellant or in another solvent.

The solids 24 in the capsule or case 23 consist of a mixture in finely divided or granular form and comprise as one ingredient a substance serving as the bulking material and as another ingredient, a flocking agent, the combination of these ingredients, when sprayed, forming a fluffy, white, snow-like coating. More especially, the bulking material is one of the higher members of the series of fatty acids, which are white, waxy solids at ordinary temperatures. A suitable active solid material for the purpose consists essentially of stearic acid, which in commercial form may contain palmitic acid. This solid material is easily soluble in propellents of chlorinated type, such as the propellents contemplated in accordance with the present invention and described above.

The resinous material is desirably a polymer of polyvinyl acetate, which is colorless and transparent and which will dissolve in the propellant contemplated in accordance with the present invention. This particular resinous material is desirable because of its high solubility in the propellant, permitting thereby the production of an aerosol container unit having a larger proportion of dissolved solids than is permissible with other types of resins. Another resin which is suitable but which does not allow for such a high proportion of dissolved solids is an acrylic resin, such as "Lucite," consisting essentially of a copolymer of n-butyl and iso-butyl methacrylate in approximate proportions 50-50.

The solid composition may be white, if a white decorative surface in imitation of snow is desired, or may contain coloring matter in case a tinted or colored surface coating is required.

An example of a highly desirable formulation for the solids 24 in the cartridge 22 consists essentially of ½ stearic acid (including palmitic acid, if any) by weight and ½ polymer of polyvinyl acetate (Gelva V-15-R), and an example of a suitable propellant for such solids consists essentially of a 30-70 blend of methylene chloride (technical grade) and Freon 12. With this exemplified makeup of the container unit, the cartridge case 23 and/or cap 26 may be of polystyrene, which will dissolve readily in the propellant. In such a make-up, the solids 24 (bulking material and the resin) constitute 9% of the combined solids and propellant, but because of the high solubility of the polymer of polyvinyl acetate in the propellant, these solids may be increased to 14 or 15%.

Another example of a highly desirable formulation for the solids 24 in the cartridge 22 consists essentially of ½ stearic acid (including palmitic acid, if any) by weight and ½ methacrylate resin polymer (Lucite 46"). With an acrylic resin polymer, the use of methylene chloride as one of the propellant ingredients is not so suitable be-

cause of the insolubility of this resin in methylene chloride. For that reason, the propellant used with this solid composition is a 50-50 blend of Freon 12 and Freon 11. The percentage of solids in the container unit could be about 9%.

In preparing the capsule 22, the two ingredients of the solid composition 24 may either be poured into the cases 23 separately in the right proportions, or the two solid ingredients may be premixed in the right proportions and the mixture then poured into the cases. The cases 23 are then closed with the caps 26, one on either end, and the junctures therebetween sealed with a suitable sealing material, such as toluol.

Loading of the containers 10 may be effected either with pressurized equipment at room temperature to maintain the propellant in liquid form as it is poured into the container, or with the propellant at sub-zero temperature, so that the propellant may be handled as a liquid. In either case, the cartridge 22 containing the required amount of solids and the required proportions of ingredients (bulking material and resin) is dropped into the container 10 through its top opening 12, and the propellant 20 poured therein. Under these conditions the cartridge will not disintegrate and its contents will not blow out into the atmosphere, as the propellant is poured into the container. The valve cup 13 with attached valve 14 and standpipe 17 is then crimped and sealed onto the container body 11 over its top opening 12.

Instead of a single long cartridge containing the necessary solids, two shorter cartridges may be employed for each container unit, especially where a large percentage of solids is required. One cartridge, for example, may contain the essential coating solids and the other cartridges may contain the resin, or both cartridges may contain the mixture of these solid ingredients. Each of these smaller cartridges would preferably have a case and a cover, one or both of these being soluble in the propellant.

The elongated shape of the cartridge 22 illustrated, is particularly suitable to permit the loading of said cartridge in the container body 11 through the restricted opening 12 at the top. In certain loading operations, however, the container is loaded through the bottom, while the bottom is removed. In that case, the cartridge may be of wider dimension relative to its lengths and, for example, may be cup-shaped.

While the invention has been described with particular reference to a specific embodiment, it is to be understood that it is not to be limited thereto but is to be construed broadly and restricted solely by the scope of the appended claims.

The invention claimed is:

1. In an aerosol container spray unit of the portable hand type, the combination including a container, a solid in said container comprising a mixture of different ingredients held together originally as a self-contained cartridge unit when charged into said container, and a liquid propellant in said container having the property of disintegrating said cartridge unit and separating said solids into finely divided sprayable form.

2. In an aerosol container unit of the portable hand type for spraying surface coating compositions, the combination comprising a container, a solid in said container comprising a mixture of a fatty acid of the higher series and a resin held together originally as a self-contained unit when charged into said container, and a liquid propellant of low boiling point in said container having the property of disintegrating said cartridge unit and dissolving said solid.

3. In an aerosol container spray unit of the portable hand type, the combination including a container, a cartridge unit in said container comprising a case and a solid therein consisting of a mixture of different ingredients, and a liquid propellant of low boiling point in

said container having the property of dissolving at least a part of said case and of dividing and separating said solids into finely divided sprayable form.

4. In an aerosol container spray unit, the combination as described in claim 3, wherein said case is made entirely of material soluble in said propellant.

5. In an aerosol container spray unit, the combination as described in claim 3, wherein said case consists of a body made of material insoluble in said propellant and a closure therefor made of a material soluble in said propellant.

6. In an aerosol container spray unit of the portable hand type, the combination including a container, a cartridge unit in said container comprising a case having at least a part thereof made of polystyrene and a solid in said case consisting of a mixture of different ingredients, and a liquid propellant in said container consisting essentially of one of the Freons having the property of dissolving polystyrene and of dividing and separating said solids into finely divided sprayable form.

7. In an aerosol container spray unit of the portable hand type for producing a coating in simulation of snow, the combination including a container, a cartridge unit in said container comprising a case having at least a part thereof made of polystyrene and a solid in said case consisting essentially of stearic acid and a resin of the class consisting of polyvinyl acetate and acrylic resin, and a liquid propellant in said container consisting essentially of one of the Freons having the property of dissolving polystyrene and of dissolving said solids.

8. In an aerosol container spray unit of the portable hand type for producing a coating in simulation of snow, the combination including a container, a cartridge unit in said container comprising a case having at least a part thereof made of polystyrene and a solid in said case consisting essentially of stearic acid and polyvinyl acetate in approximate proportions of 2 to 1 by weight, and a liquid propellant in said container consisting of at least 50% dichlorodifluoromethane (Freon 12).

9. In an aerosol container spray unit for producing a coating in simulation of snow, the combination as described in claim 8, wherein said liquid propellant consists essentially of a blend of dichlorodifluoromethane (Freon 12) and methylene chloride in proportions of approximately 70 to 30.

10. In an aerosol container unit of the portable hand type for producing a coating in simulation of snow, the

combination including a container, a cartridge unit in said container comprising a case having at least a part thereof made of polystyrene and a solid in said case consisting essentially of stearic acid and methacrylate resin (Lucite) in approximate proportions of 2 to 1 by weight, and a liquid propellant in said container consisting of at least 50% dichlorodifluoromethane (Freon 12).

11. In an aerosol container unit for producing a coating in simulation of snow, the combination as described in claim 8, wherein said liquid propellant consists essentially of a blend of dichlorodifluoromethane (Freon 12) and trichloromonofluoromethane (Freon 11) in proportions of approximately 50 to 50.

12. The method of producing an aerosol container unit of the hand portable type, comprising the steps of providing a container with an opening therein, providing a capsule that is disintegratable by the propellant employed to create pressure within said container, substantially filling said capsule with finely divided granular solids, sealing said capsule closed, placing said capsule in said container, pouring the propellant in liquid form into said container, sealing the opening in said container, said propellant reacting with said capsule to release said solids, affixing a valve to said container to release pressure formed in said container by said propellant, said valve movable by outside pressure to release a mixture of the propellant and granular solids which have been freed from said capsule and are mixed with said propellant.

13. The method of producing an aerosol container unit of the hand portable type, comprising the steps of providing a container with an opening therein, providing a capsule, substantially filling said capsule with finely divided granular solids, sealing said capsule closed with a material disintegratable by a propellant, placing the capsule in said container, pouring the propellant in liquid form into said container, sealing the opening in said container, and affixing a valve to said container to release pressure formed inside said container by said propellant, said valve being movable by outside pressure to release the propellant and the granular solids which have been freed from said capsule.
